KNITTING BAG OR SIMILAR ARTICLE

Harry Kittner, New York, N. Y., assignor to David Traum Company, Inc., a corporation of New York

Application January 22, 1953, Serial No. 23,251

Term of patent 7 years

(Cl. D3—19)

To all whom it may concern:

Be it known that I, Harry Kittner, a citizen of the United States and residing at New York, in the county of New York and State of New York, have invented a new, original, and ornamental Design for a Knitting Bag or Similar Article, of which the following is a specification; reference being had to the accompanying drawing, forming part thereof, and in which:

Fig. 1 is a perspective view of a knitting bag showing my new design.

Fig. 2 is an end elevational view thereof drawn on larger scale and showing the end opposite to that shown in Fig. 1, and

Fig. 3 is a perspective view thereof as it appears in open position.

I claim:

The ornamental design for a knitting bag or similar article, substantially as shown.

HARRY KITTNER.
